CLAIM

The ornamental design for a sound reducing enclosure, as shown and described.

DESCRIPTION

FIG. 1 is front perspective view of an implementation of a design of a sound reducing enclosure;

FIG. 2 is a front view thereof;

FIG. 3 is a left side view thereof, the right side being a mirror image;

FIG. 4 is a top view thereof; and,

FIG. 5 is a bottom view thereof.

All broken lines represent unclaimed features of the article to which the design is applied.
